Primary Examiner — Kevin K Rudzinski*Assistant Examiner* — Woosuk K Shin(74) *Attorney, Agent, or Firm* — McDonald Hopkins LLC(57) **CLAIM**

The ornamental design for a garment as shown and described.

DESCRIPTION

FIG. 1 is a perspective view including the front, top and side of a garment showing my new design;

FIG. 2 is a perspective view including the back, top and opposite side of the garment of FIG. 1;

FIG. 3 is a front elevation view of the garment of FIGS. 1 and 2;

FIG. 4 is a back elevation view of the garment of FIGS. 1-3; FIG. 5 is a side elevation view of the garment of FIGS. 1-4; and,

FIG. 6 is an opposite side elevation view of the garment of FIGS. 1-5.

The broken lines in the figures depict portions of the garment that form no part of the claimed design.

1 Claim, 6 Drawing Sheets(56)
